UNITED STATES PATENT OFFICE.

WILLIAM HERBERT NIELD, OF STOCKPORT, ENGLAND, ASSIGNOR OF ONE-HALF TO
WILLIAM MELLAND, OF MANCHESTER, ENGLAND.

POWER-PRODUCING SYSTEM.

Application filed December 8, 1919. Serial No. 343,272.

To all whom it may concern:

Be it known that I, WILLIAM HERBERT NIELD, subject of the King of Great Britain, residing at Stockport, in the county 5 of Chester and Kingdom of England, have invented certain new and useful Improvements in Power-Producing Systems, of which the following is a specification.

The present invention relates to an im- 10 proved power producing system.

An object of this invention is to get a greater output of energy from the coal fuel than has hitherto been possible by burning the coal under a boiler of an ordinary grate.

15 A further object of this invention is to avoid the loss by combustion of valuable by-products such as tar, ammonia, toluol and the like.

The invention is more particularly de- 20 scribed with reference to the accompanying diagrammatic drawing.

In the drawings the invention is shown at applied to a boiler taken by way of example but the invention is applicable to any type 25 of heating furnaces using coal as fuel.

Fuel such as coal, 1, is fed to a hopper 2, and from thence passes to a tube 3, in which operates a continuously moving conveyor 4, driven from a source of power 5, 30 in any desired manner. The tube 3 projects into the furnace and is subject to the heat of the fire bed 6, on all sides. Consequently the coal in this tube will be partially coked and will fall on the moving 35 grate 7, in a partially coked condition. This grate may be a chain grate moving in the direction of the arrow 8, so that ash automatically passes over the dumping plate 9, and is discharged from the furnace.

40 The gases evolved during the coking of the fuel in the tube 3, pass up a stack 10, and are not passed into the furnace where the valuable by-products would also be burnt. These are therefore aspirated into 45 the stack 10, by means of a fan 11, and are then passed through a condenser 12, which may be of any usual form for instance containing liquid tar which is adapted to be drawn off by a pipe 13 as required. This 50 will remove a large portion of the tar from the gases. The gases then pass into a pipe

14 and upwards through a condenser 15 in an opposite direction to a stream of water passing downwards through a circulating pipe 16. Ammonia liquor can be drawn off 55 by means of the stop cock 17. The gases having been deprived of ammonia then pass into a pipe 18 and thence through a condenser 19 through which heavy oil is being circulated to remove the liquid hydrocar- 60 bons from the gas.

The condensers 15 and 19 are diagrammatic only and any apparatus may be substituted therefor for removing the desired products from the gas. 65

The gas after having been stripped of all these valuable products can then be passed, by means of a conduit 20 and cock 21 to a burner 22, to be burnt in the furnace as an additional source of heat energy 70 therefor.

Means may be provided to short circuit, when desired, the condensing apparatus 19 by means of a cock 23.

I declare that what I claim is:— 75

A fuel consuming device comprising a furnace for industrial use including a grate to consume the fuel, a tube in the combustion chamber of the furnace, means to pass fuel continuously into said tube and out of 80 the inner end on to said grate, means to move the fuel passing out of said tube on to said grate along the grate in an opposite direction to the direction of its passage through the tube, means to discharge ash from the 85 furnace, means to draw off gases from the tube evolved in the absence of air, means to remove condensation products from the gases, means to pass the stripped gases back to the furnace and a burner in the combustion chamber to burn said stripped gases below the tube to coke the fuel therein previous to its passing on to the grate. 90

In witness whereof, I have hereunto signed my name this 10th day of October, 95 1919, in the presence of two subscribing witnesses.

WILLIAM HERBERT NIELD.
